CLAIM

The ornamental design for an aircraft, as shown and described.

DESCRIPTION

FIG. 1 is a perspective view showing the front, top and left side of an aircraft which forms my new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a front elevational view thereof; and,

FIG. 7 is a rear elevational view thereof.

The broken lines in the drawings depict portions of the aircraft that form no part of the claimed design.
